(57) **CLAIM**

The ornamental design for a packaging container with surface ornamentation, as shown and described.

DESCRIPTION

FIG. 1 is a perspective view of packaging container with surface ornamentation embodying our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top view of the packaging container in an unfolded state; and,

FIG. 9 is a top view of a second embodiment of the packaging container in an unfolded state. Front, rear, left, right, top and bottom views thereof are the same as those of FIGS. 2–7.

The broken lines in the drawing represent unclaimed environmental subject matter.
